GAS TREATING APPARATUS

William J. Harshaw, Shaker Heights, Ohio, assignor to The Harshaw Chemical Company, Elyria, Ohio, a corporation of Ohio

Application April 30, 1941, Serial No. 391,190

6 Claims. (Cl. 183—4)

This invention relates to desiccating or similarly conditioning gases, and has for its principal object to provide apparatus for desiccating or similarly conditioning air or other gases in a compartment, container or other closed or substantially closed space. More specifically, the object is to provide superior apparatus involving the use of suitably shaped bodies principally composed of aluminum oxide or similar material capable of absorbing water or other vapor from a gaseous medium, and reconditioning of such bodies after use.

A further object is to provide improved apparatus embodying means for circulating gases in contact with suitably shaped bodies of aluminum oxide or the like in a suitable chamber, and heating means in such chamber for driving off water or other vapors absorbed by such bodies without removing them from such chamber.

Other and more limited objects will be in part apparent and in part pointed out hereafter in connection with the accompanying drawing, wherein Fig. 1 is a schematic view showing in plan an apparatus embodying the invention; Fig. 2 is a transverse section through one unit of the apparatus shown in Fig. 1 with the air flow conduits and solid adsorbent bodies omitted for clearness; Fig. 3 is an enlarged plan view of said unit showing a portion of the interior structure in dotted outline; Fig. 4 is a fragmentary detail view showing one of the heating elements with desiccating bodies in position thereon; Fig. 5 is an enlarged sectional view showing a desiccating body in position on a modified form of heating element; and Fig. 6 is a fragmentary view taken at right angles to the view of Fig. 5.

Referring now to the drawing, the numeral 10 indicates generally an enclosure which may be a compartment to be air-conditioned. Within the compartment 10 is a pair of units 11 and 12 which will be referred to and described as air-conditioning units, although it is to be understood that they may be used for removing vapors from gases in general. Air is forced through the units 11 and 12 by means of a pump 13 which delivers to one or the other of the units 11 and 12 depending upon the setting of the valves 14, 15 and 16. The air passing through the unit is delivered back to the compartment or to the exterior thereof depending upon the setting of the valves 15 and 16.

With the valves 14, 15 and 16 set as shown in the drawing, air will pass from the compartment through the desiccating unit 12 and return to the compartment, being dried during its passage

therethrough. If now the valve 14 is moved to a position to cut off all air from the unit 12, air will pass through the unit 11 and return to the compartment. If the valve 14 be set at mid position, both the units can be used for desiccating at the same time.

It will be clear from the drawing that the outlets from each of the units 11 and 12 are capable of directing air either to the interior of the compartment or to the exterior thereof through the conduits 17 depending upon the setting of the valves 15 and 16. It is therefore clearly possible to operate one or both units for desiccating and to pass air through one or both units for reconditioning. The preferred operation, however, consists in setting the valve 14 in an intermediate position so that most of the air goes through the unit which is being used for desiccating and returns to the compartment while a minor portion goes through the other unit, the desiccant in which is being reconditioned, and is discharged to the outside of the compartment, it being understood that the compartment is not absolutely air-tight.

One detailed construction of the units 11 and 12, which are identical, is indicated in Fig. 2 wherein is shown a housing made up of a bottom portion 18 and a cover 19, the cover 19 being composed of heat resistant electrical insulating material, suitably, ceramic material. Attached to the cover 19 are angle members 20 and 21 to which are connected conductors 22 and 23d. Extending between the angle members are heating elements in the form of rods or wires 23 composed of high resistance metal so that when current is passed therethrough, they will be highly heated. Received on the heating elements 23, as indicated in Fig. 4, are the desiccating bodies 24 which may be composed of aluminum oxide or the like. It is to be understood that there are numerous heating rods 23 only one tier thereof being shown in Fig. 2. These are spaced as closely as possible to afford room for the desiccating bodies 24 to be received thereon.

If desired, the heating elements 23 may take the form of thin walled tubes 23a or helical coils. The shape of the desiccating bodies indicated is merely representative, and these bodies may take other shapes. I prefer that they be annular and received on heating elements 23, but it is within the scope of the invention to place in the units 11 and 12 desiccating bodies of other shapes, for example, cylindrical pellets or irregularly shaped bodies or granules. In such case, the heating

elements 23 nevertheless will be effective to drive out moisture from the desiccating material.

Having thus described my invention, what I claim is:

1. In apparatus for the removal of vapors from gases, a plurality of absorptive bodies capable of absorbing such vapors, each of said bodies having a thickened portion within its circumference and an opening through the thickened portion thereof and an elongated heating element on which said absorptive bodies are received in a beadlike series, said heating element passing through said openings.

2. In gas conditioning apparatus, means enclosing a gas conditioning chamber, electrical heating means in said chamber, solid absorptive bodies with openings therethrough and positioned beadlike on said electrical heating means, means for causing gas to pass through said chamber and means for selectively energizing or de-energizing said electrical heating means whereby the solid absorptive bodies may be reconditioned by heating without being removed from said chamber.

3. In an apparatus for removal of vapors from gases, an elongated heating element, an absorptive body capable of absorbing such vapors, having a thickened portion well within the circumference of the body, the thickened portion having an opening therethrough of sufficient size for mounting on said heating element, a plurality of said absorptive bodies all received beadlike

in circumferential alignment on said heating element.

4. In an apparatus for removal of vapors from gases, an elongated heating element, a circular absorptive body centrally thickened, capable of absorbing such vapors and having an opening therethrough, a plurality of said absorptive bodies received beadlike on the heating element whereby said bodies cannot be packed together circumferentially.

5. In an apparatus for removal of vapors from gases, an elongated heating element, an annular absorptive body capable of absorbing such vapors, the annulus being thickened around the opening, a plurality of said absorptive bodies all being received beadlike on the heating element.

6. In gas conditioning apparatus means enclosing a gas conditioning chamber, electrical heating means in said chamber, solid absorptive bodies composed principally of active aluminium oxide with a thickened portion and having an opening through the thickened portion, said bodies being positioned on said electrical heating means, whereby only the thickened portions of the faces contact, means for causing gas to pass through said chamber and means for selectively energizing and de-energizing said heating means whereby the solid absorptive bodies may be reconditioned by heating without being removed from said chamber.

WILLIAM J. HARSHAW.
